UNITED STATES PATENT OFFICE.

JOHN F. COURSON, OF PITCAIRN, PENNSYLVANIA.

DRAFT-GEAR.

1,205,712.

Specification of Letters Patent.

Patented Nov. 21, 1916.

Application filed September 11, 1913. Serial No. 789,279.

To all whom it may concern:

Be it known that I, JOHN F. COURSON, citizen of the United States, residing at Pitcairn, in the county of Allegheny and State of Pennsylvania, have invented certain new and useful Improvements in Draft-Gears, of which the following is a specification.

My invention consists of an improvement in draft gears for railway cars, etc., and has for its object to provide a gear of simple construction and high efficiency, designed to utilize the resisting power of springs cumulatively, and the wedging and releasing qualities of wedge blocks, co-acting with the housings or casings therefor for effecting cumulative resistance, said elements being arranged between a central buffing member and a rear resisting member, arranged and adapted to effect compression of the spring members upon longitudinal movement of either of such terminal members, and the creation of resisting friction through the wedge block construction.

The invention, as shown, discloses certain novel arrangements of expanding friction-creating wedge blocks and a co-acting separating wedge having front and rear wedge members, similar to that disclosed in my prior application filed May 29, 1913, Serial No. 770664.

The invention as disclosed also embodies certain novel means for effecting supplemental frictional resistance by means of additional friction members mounted with the main friction shoes and operable independently thereof for movement in either direction, together with the installation of the apparatus in the car framing and the several parts necessary thereto, to carry out the functions of the apparatus.

One of the particular objects of the invention is to so arrange resisting springs, with relation to the central drawbar and its follower, or the like, and an opposing resisting follower or equivalent means, whereby to effect preliminary separation of and opposition by a spring and supplemental operation and resistance by an additional spring, said springs being compactly mounted and arranged within the limited space provided in such gears.

These objects are accomplished, in preferred forms of the apparatus, hereinafter

described, as illustrated in the accompanying drawings, in which—

Figure 1 is a central longitudinal vertical sectional view of the complete apparatus in normal position, indicated by the section line I. I. of Fig. 2. Fig. 2 is a longitudinal horizontal sectional view, indicated by the line II. II. of Fig. 1. Fig. 3 is a cross sectional view, indicated by the line III. III. of Fig. 1, omitting the central wedge. Figs. 4 and 5 are detail views in perspective of the wedging friction shoes. Fig. 6 is a similar view of the central compound wedge member. Fig. 7 is a transverse sectional view on the line VII. VII. of Fig. 2. Fig. 8 is a sectional view, similar to Fig. 1, taken on the line VIII. VIII. of Fig. 9, showing a modified construction, utilizing a tapered wall casing and grooved wedges. Fig. 9 is a sectional view, similar to Fig. 2, taken on the line IX. IX. of Fig. 8. Fig. 10 is a transverse sectional view, taken on the line X. X. of Fig. 8, omitting the central wedge. Fig. 11 is a detail perspective view of the central wedge, like Fig. 6, showing additional friction ridges and grooves. Fig. 12 is a similar view of one of the friction shoes provided with co-acting grooved and ribbed wedging faces. Fig. 13 is a detail sectional view showing the wedging friction shoes and central wedge within the casing and provided with supplemental friction strips. Fig. 14 is a perspective detail view showing one of said friction shoes provided with a receiving groove for such supplemental member. Fig. 15 is a perspective detail view showing one of such supplemental friction members.

In the drawings, 2 represents the drawbar of a coupler fixedly connected with the yoke 3 by transverse bolts 4 in the manner customary in this art, said yoke embracing the casing 5 at top and bottom, as shown, the yoke and casing being located between the central sills 6, 6. A bearing block or follower piece 7 is set against the rear end 100 of casing 5 and its closing end wall, herein-after described, against the outer end of which follower 7 bears the rounded end 8 of yoke 3 with an interposed filling block 9, preferably secured to the end of the yoke. 105

The front stops 10 extend inwardly from each side of the center sill 6, which sustain the pulling of the draft gear and impart it

to said sills, while similar rear stops 10' act to receive and impart buffing strains in the same manner.

The casing 5 is generally cylindrical in cross section and is mounted between the sills 6, supported upon any suitable cross member 11 between the sills, having suitable clearance for the yoke 3.

In front of follower 7, with sufficient intervening clearance to allow for the absorbing action of the gear, are additional stops 20, 20, secured like stops 10 and 10' to the sills 6 and providing rigid bearing abutments for the forwardly moving follower 7.

15 Within the forward portion of the casing 3, in the construction shown, are assembled 3, in the construction shown, are assembled and nested series of segmental shaped shoes 12, 12, and 13, 13, respectively, having co-acting wedging faces 14 and 15 respectively.

20 These several friction shoes are designed to be assembled, as shown in the drawings, within the cylinder and to effect lateral expansion or separation and resulting frictional engagement against the inner face of 25 the cylinder and between their contacting faces, upon the occurrence of either buffing or pulling shocks, and to also freely separate or collapse upon termination of pressure. To this end one set or pair of the wedging

30 friction shoes 13, 13, preferably extend forwardly beyond the intervening co-acting shoes 12 by projections 16, adapted to receive the force of impact from the drawbar in buffing, through the central wedge member

35 B. The companion friction shoe members 12, 12, preferably extend correspondingly rearwardly of the members 13 a sufficient distance to engage one of the rear resisting members, as the absorbing spring 17 placed 40 within the rear portion of the casing 3, with its companion spring 18.

Between the drawbar 2 and a central wedge B is interposed a transverse follower 19 adapted to engage front stops 10, the 45 similar follower 7 being interposed between the rear end of the casing and rear stops 10'. Central wedge B is provided with front and rear oppositely disposed wedging faces b, b, and b', b', respectively, adapted to engage 50 co-acting corresponding wedge faces 21, 21, and 22, 22, of wedging friction shoes 13, and to effectually and simultaneously transmit separating action to the front and rear portions of said shoes under buffing or pulling 55 strains, and to expand said shoes against the casing.

The co-acting friction shoes 12, which extend rearwardly of shoes 13, may be provided with shouldered recesses or cavities 23 at their rear ends for the resisting spring 17, hereinafter described, or they may merely abut against stronger spring 18' in the reversed position shown in Fig. 9.

In Figs. 8 to 15 inclusive, the same general construction as above described is

shown, the central wedge B' having shoulders corresponding to wedge shoulders b and b', but provided with corrugations or ridges b², b³, respectively, the co-acting friction shoes 13' having similarly disposed wedge 70 faces 21' and 22' having co-acting ridges and grooves interfitting therewith. The friction shoes 13' are also provided with the tapered lateral wedging faces 15' adapted to co-act with the corresponding wedge faces 75 14' of the companion wedge members 12'. The object of the corrugations and grooves b², b³, and 21', 22', is to increase the wedging surface.

In Figs. 13, 14 and 15, the friction shoes 80 13'' are provided with the wedging and friction-creating surfaces above described, and are also provided with longitudinal grooves or recesses 24 adapted to receive the supplemental friction strips 25 having the 85 front retaining lip 26. Said friction strip and its lip, one or more being provided for each of the friction shoes, are so disposed as to effect supplemental movement upon engagement by the follower 19' at the latter 90 portion of the stroke, for thrusting the strip inwardly within grooves 24, for supplemental friction, and to be withdrawn upon termination of the pressure, by outward movement of the central wedge block B'' 95 and its shoulders 27, provided for such purpose. By this means it will be observed that the movement of the strips 25 is effected after the partial distending of the main friction shoes 13'', by wedge B'' providing for 100 supplemental and additional friction.

It will be obvious that the number, arrangement or form of the strips 25 may be changed or varied according to the construction or conditions of use, their purpose being to supplement the initial frictional engagement between the shoes and the cylinder.

The cylinder 5', as shown in Figs. 8 to 13 inclusive, is interiorly tapered, as at 5^a, providing increased binding frictional engagement between the casing and the wedging friction shoes 12' and 13', so that as these shoes are expanded by the central wedge B' or B'' they will be forced tightly within the tapering front portion of the casing. Where 11 the supplemental friction strips 25 are employed, their action on the casing will be increased in the same manner. Wherever parts similar to those already described are shown in the drawings on Sheet 2 they are 12 referred to by the same numerals, primed.

Referring to the spring construction, as shown in Figs. 1 and 2, it will be observed that springs 17 and 18 are arranged the one within the other for a considerable portion 12 of their length and within the limited clearance space between the rear portion of the friction-creating members and the rear opposing abutment, i. e., either the end of the casing 5, or follower 7. A supporting stir- 13

up, yoke or cup 28 is interposed between the springs, having the rear bottom portion 29 for opposing the rear end of spring 17, and the laterally extending collar or flange 5 30 for engagement against the front end of spring 18. By this means, spring 17 being preferably weaker than spring 18, it will be compressed and effect opposing resistance for the initial portion of closing shocks or 10 strains, and upon compression, will transmit movement through the cup or housing 29 and its flange 30 to the heavier spring 18. Said spring, upon further movement, will also be compressed, providing resistance, 15 supplemental or in addition to the resistance of spring 17.

Figs. 8 and 9 show the springs 17' and 18' and the yoke 28' in reversed position, the heavier spring 18' bearing directly against 20 the wedge-friction shoes 12' and acting to first compress the weaker spring 17' through the yoke. The operation is however the same as above described, the springs compressing successively, the one within the 25 other.

It will be understood that the arrangement of the springs, as shown and described, may be adopted with any other form of draft gear not necessarily having the forward 30 friction-creating members.

What I claim is:

1. In a draft gear, the combination with a rear abutment and a relatively movable drawbar, of a casing, a drawbar, a central 35 wedge abutting toward the drawbar, a cylindrical series of assembled friction shoes within the casing having lateral co-acting longitudinally operative wedge faces, the alternating friction shoes having inwardly 40 extending wedge portions directly engaging the central wedge.

2. In a draft gear, the combination with a rear abutment and a relatively movable drawbar, of a casing, a drawbar, a central 45 wedge provided with front and back wedge faces, a cylindrical series of assembled friction shoes within the casing having lateral co-acting longitudinally operative wedge faces, the alternating friction shoes having 50 inwardly extending wedge portions directly engaging the central wedge.

3. In a draft gear, the combination with a rear abutment and a relatively movable drawbar, of a casing, a drawbar, a central 55 wedge abutting toward the drawbar, a cylindrical series of assembled friction shoes within the casing having lateral co-acting longitudinally operative wedge faces, the alternating friction shoes having inwardly 60 extending wedge portions directly engaging the central wedge and the other friction

shoes extending inwardly beyond said alternating shoes.

4. In a draft gear, the combination with a rear abutment and a relatively movable 65 drawbar, of a casing, a drawbar, a central wedge, a cylindrical series of assembled friction shoes within the casing having lateral co-acting wedge faces, the alternating friction shoes having inwardly extending wedge portions engaging the central wedge and the other friction shoes extending inwardly beyond said alternating shoes, and a spring seating against said inwardly extending shoes and interposed between 70 them and the rear abutment.

5. In a draft gear, the combination with a rear abutment and a relatively movable drawbar, of a casing, a drawbar, a central wedge, a cylindrical series of assembled 80 friction shoes within the casing having lateral co-acting wedge faces, the alternating friction shoes having inwardly extending wedge portions engaging the central wedge and the other friction shoes extending 85 inwardly beyond said alternating shoes, and a pair of separated springs interposed between the rear abutment and said friction shoes, one of said springs bearing against the inwardly extending bearing shoes, and 90 the other bearing against the rear end of the casing.

6. In a draft gear, the combination with a rear abutment and a relatively movable drawbar, of a casing, a drawbar, a central 95 wedge abutting toward the drawbar, a cylindrical series of assembled friction shoes within the casing having lateral co-acting longitudinally operative wedge faces, the alternating friction shoes having inwardly 100 extending wedge portions directly engaging the central wedge and provided with supplemental friction strips.

7. In a draft gear, the combination with a rear abutment and a relatively movable 105 drawbar, of a casing, a drawbar, a central wedge abutting toward the drawbar, a cylindrical series of assembled friction shoes within the casing having lateral co-acting wedge faces, the alternating friction shoes 110 having inwardly extending wedge portions directly engaging the central wedge and provided with supplemental friction strips having portions adapted to be engaged by the central wedge.

In testimony whereof I hereunto affix my signature in the presence of two witnesses.

JOHN F. COURSON.
